UNITED STATES PATENT OFFICE

ALBERT M. JOHNSON, OF ROCKFORD, ILLINOIS, ASSIGNOR TO BARNES DRILL COMPANY,
OF ROCKFORD, ILLINOIS, A CORPORATION OF ILLINOIS

HONING MACHINE

Application filed April 28, 1930. Serial No. 447,854.

The invention relates to honing machines of the type in which one or more rapidly rotating honing tools are reciprocated by hydraulic means for the purpose of producing a smooth, highly finished surface upon the interior of a hollow cylindrical body.

Such machines have heretofore been applied for the most part to the finishing of internal combustion engine cylinders arranged in blocks of four, six or eight as the case may be. When thus applied, only a relatively short stroke is required of the honing tools. The honing process may, however, be applied to great advantage to other cylindrical bodies such, for example, as Diesel engine cylinders, air cylinders and steam locomotive cylinders, but in view of the widely varying range in sizes it is necessary to provide machines of correspondingly different sizes. It is therefore one object of my invention to provide a honing machine of such construction that it can be manufactured economically in a varying range of sizes.

The larger cylinders must usually be operated upon singly and such machines involve the use of a single spindle which is reciprocated by a hydraulically actuated means including a piston and cylinder capable of a stroke corresponding to or slightly exceeding the length of the work. The length of such cylinders run as high as 54 inches, necessitating a spindle stroke of 56 inches, and usually the work is of substantial diameter so that the force applied to the spindle to reciprocate the same must be very substantial in character. At the same time it is very desirable to maintain the overall dimensions of the machine as small as possible. With this in view a further object of my invention is to provide a honing machine embodying a novel arrangement of the spindle, its hydraulic reciprocating means, and the means for rotating the same, such that the force applied for reciprocating purposes is well balanced to insure a true axial thrust on the spindle, while at the same time the overall length of the machine is minimized.

The above and other objects are attained through the provision of a honing machine having a separately formed transmission cas-

ing which, in the case of a vertical type machine, may be mounted on the top of a column with a portion thereof projecting over the side of the column, a splined drive spindle extending through the transmission casing and having a head at its lower end, a pair of actuating bars or rods slidably guided along opposite sides of the casing for movement parallel to the drive spindle and connected to the head on opposite sides of the spindle, together with hydraulic means for simultaneously actuating the two rods whereby to apply a balanced actuating force to the head for reciprocating the same, the two rods also serving to prevent rotation of the head by the drive spindle.

Other objects and advantages will become apparent from the following description taken in connection with the accompanying drawings, in which:

Fig. 1 is a side elevational view of a honing machine embodying the invention in its preferred form.

Fig. 2 is an enlarged front elevational view of the transmission casing, the drive spindle and the means for reciprocating the drive spindle.

For purposes of disclosure the preferred form of the invention is illustrated in the drawings and will hereinafter be described in detail as applied to a vertical type honing machine, but it is to be understood that this disclosure is not intended as a limitation of the invention to this type of machine, it being contemplated that various changes might be made by those skilled in the art to adapt the invention to other types of machines without departing from the spirit and scope of the invention as defined by the appended claims.

The invention, as herein illustrated, is applied to a honing machine of the vertical type, including a frame structure having a transmission casing 10 supported on the top of a column 11 with a spindle bearing head 10a in the form of a vertical cylindrical portion of the casing positioned in overhanging relation to the side of the column. A splined drive spindle 12 extends axially through the projecting cylindrical portion 10a of the cas-

ing and is movable longitudinally through the casing toward and away from a work support 11^a positioned in front of the column 11.

- 5 The casing 10 houses suitable reduction and speed change gearing of a well known character, driven by a motor 13 mounted on the column, and including a gear 14 positioned in the cylindrical portion 10^a of the casing 10 and engaging the splines 12^a of the spindle 12. When a single honing tool 15 is to be rotated by the spindle, the tool may be mounted directly on the lower end of the spindle 12.

In the use of the machine, the tool 15 is 15 simultaneously rotated and reciprocated within a piece of work such as a cylinder 16, and the reciprocatory movement is obtained by hydraulically operated means. To avoid increasing the overall length of the machine 20 and at the same time apply a true axial thrust to the spindle, I employ two piston and cylinder devices, one on each side of the portion 10^a of the casing. Of these devices the cylinders 17 are secured on opposite 25 sides of the casing 10 parallel to the spindle 12, and pistons 17^a in said cylinders have their rods 18 connected on opposite sides of the spindle to a head 19 in which the lower end of the spindle is rotatably journaled. 30 Since the piston rods 18 are connected to a head 19 eccentrically of the spindle axis, they serve not only to transmit reciprocatory movement to the head and the spindle, but also function to prevent rotation of the head 35 by the spindle.

With this arrangement of the rotating, reciprocating and guiding means, substantially the entire length of the spindle 12 may be splined whereby to avoid undue length of 40 the spindle. The only portion of the spindle 12 which does not function as a sliding connection during reciprocation of the head is that portion which lies between the lower end of the splines 12^a and the head 19. Thus 45 the length of the unsplined portion is determined by the position of the gear 14 in the casing 10 and since it is not dependent upon the size of the machine it may be made of the same length in large or small machines.

50 In constructing a machine of the character herein disclosed for any given size of work, it will be apparent that within reasonable limits, a transmission casing 10 of the same size and construction may be employed and the other elements of the machine may be assembled about the casing 10 to provide for the desired length of stroke of the honing tool 15. To facilitate the assembly of the machine, the cylindrical portion 10^a of the casing 10 has transversely extending headers 18^a at its upper and lower ends, shaped to receive the cylinders 17 on their opposite sides, and the cylinders are clamped in position by cap screws 20^a extending through lugs on the lower cylinder

heads 20 and engaging the lower header 18^a. The cylinders are held against the upper header 18^a by clamps 21 which embrace the cylinders and are detachably secured to the header by cap screws 21^a. Rods 22 secured in the lower heads 20 of the cylinders and extending upwardly along the sides thereof are used to fix upper heads or caps 23 on the upper ends of the cylinders.

70 Thus it will be seen that cylinders 17 of various lengths may be secured on the casing 10 without requiring alteration of the casing or its enclosed gearing. The spindle 12 may also be made of any desired length without changing the construction or size of the 75 transmission casing 10 and without altering the arrangement of the gearing enclosed by the casing.

80 Also it will be apparent that the construction provided permits of the convenient removal of the head 19. This is of special advantage in that it enables the replacement of one head by another as, for example, when changing from a single spindle head to a 85 multiple spindle head in case it is desired to 90 operate upon two or more cylinders at the same time.

95 In constructing machines of various sizes, the vertical dimension of the column 11 is, of course, varied and if additional clearance 100 is desired between the column and the axis of the tool 15, a forward projection 24 may be formed on the upper end of the column to permit the casing 10 to be mounted forwardly of the column axis.

105 In the operation of the machine, the two pistons 17^a are simultaneously reciprocated, by pressure fluid supplied at 25 to the cylinders 17 through suitable valve-controlled connections (not shown) leading from the pump 26 mounted on the column 11 and driven by the motor 13.

110 I claim as my invention:

115 1. A honing machine comprising, in combination, a column, a work support in front of said column, a separately formed transmission casing detachably secured on said column, said casing having a portion located in overhanging relation to said work support, a driven gear in said portion, a splined spindle extending through said portion and engaging said gear, a pair of cylinders, a pair of horizontally extending headers on the top and bottom of said portion, cylinder heads engaging the lower ends of said cylinders and detachably secured to the lower one of said headers to support the cylinders on said header, clamps embracing said cylinders and detachably secured to the upper header to hold the cylinders against said upper header in parallel relation on opposite sides of said portion, heads for the upper ends of the cylinders, pistons in said cylinders having piston rods extending through said lower heads, and a transverse member 120

125

130

in which the lower end of said spindle is journaled and to which said piston rods are connected on opposite sides of the spindle.

2. A honing machine comprising, in combination, a column, a separately formed transmission casing secured on the top of said column and having a portion projecting over one edge of said column, a gear in said portion, a splined shaft extending through said portion and engaging said gear, a pair of vertically positioned cylinders, heads engaging the lower ends of said cylinders to hold the same against both lateral and downward movement, said heads being detachably secured to opposite sides of said portion adjacent the lower edge thereof, brackets engaging intermediate portions of said cylinders and detachably secured adjacent the upper edge of said portion to hold the cylinders in vertical position, heads on the upper ends of said cylinders, tie rods connecting the upper and lower heads of each cylinder, pistons in said cylinders having piston rods extending through said lower heads, and a transverse member in which the lower end of said spindle is journaled and to which said piston rods are connected on opposite sides of the spindle.

3. A machine of the character set forth comprising, in combination, a column, a work support on the lower end of said column, a separately formed head mounted on the upper end of the column and having a hollow extension disposed vertically at the forward side of the column above said work support, headers at the upper and lower ends of said extension having laterally projecting end portions, a splined spindle extending through said headers centrally thereof, a pair of separately formed hydraulic cylinders, means for clamping said cylinders to said projecting end portions of the headers in parallel relation to said spindle, pistons in said cylinders having rods depending therefrom, a cross head rigidly connecting the lower ends of said rods and having the lower end of said spindle journaled therein, and means enclosed within said casing for rotating the spindle during its reciprocation by said pistons.

4. A honing machine comprising, in combination, a column, a work support at the lower end of the column, a separately formed casing mounted upon the upper end of the column and having a hollow extension at its upper forward end disposed a substantial distance above the lower end of said casing, a splined spindle mounted centrally of said extension and parallel to the column, a pair of separately formed hydraulic cylinders of substantial length, means for clamping the lower end portions of said cylinders rigidly upon opposite sides of said extension with the upper portions of the cylinders projecting upwardly in parallel relation with the

upper end of said spindle, pistons in said cylinders having rods depending therefrom, a cross head rigidly connecting the lower ends of said rods and having the lower end of said spindle journaled therein, and means enclosed within said casing and including a gear element in said extension for rotating the spindle during its reciprocation with said head.

In testimony whereof, I have hereunto affixed my signature.

ALBERT M. JOHNSON.
